DESIGN FOR A TELEVISION ANTENNA

Rudolph Riderman, Chicago, Ill., assignor to
Precision Plastic Products, Inc., Chicago, Ill., a
corporation of Illinois

Application October 11, 1948, Serial No. 149,071

Term of patent 3½ years

(Cl. D26—14)

To all whom it may concern:

Be it known that I, Rudolph Riderman, a citizen of the United States and resident of Chicago, in the county of Cook and State of Illinois, have invented a new, original, and ornamental Design for a Television Antenna, of which the following is a specification, reference being had to the accompanying drawing, forming a part thereof.

Fig. 1 is a perspective view of a television antenna, showing my new design.

Fig. 2 is a top plan view of the same.

Fig. 3 is a side elevational view of the same.

Fig. 4 is an end elevational view of the same.

I claim:

The ornamental design for a television antenna, substantially as shown.

RUDOLPH RIDERMAN.
